UNITED STATES PATENT OFFICE.

WILLIAM L. FROSS, OF CHICAGO, ILLINOIS.

TOBACCO-BAG.

1,185,651.

Specification of Letters Patent.

Patented June 6, 1916.

Application filed December 10, 1915. Serial No. 66,079.

To all whom it may concern:

Be it known that I, WILLIAM L. FROSS, a citizen of the United States, residing at Chicago, in the county of Cook and State of Illinois, have invented new and useful Improvements in Tobacco-Bags, of which the following is a full, clear, and exact description.

Heretofore fine cut tobacco has been put up in packages of a convenient size to be carried in the pocket of the smoker, and the package to which my improvements are applied consists in a paraffin paper wrapper the end edges of which are folded in such manner as to confine and keep the air from the tobacco and keep it fresh, and also comprises a cloth bag the edges of the mouth of which are cased or hemmed and provided with two looped strings threaded through the same in such manner that by pulling the outer extensions of the same in opposite directions the mouth of the bag will pucker and be drawn closed tightly over the end of the wrapper. This arrangement was excellent for preserving the tobacco until the package was open for use. To do this the smoker tore off the label that is usually pasted over the closed mouth of the bag and then stretched open the mouth of the latter with his fingers and reaching into the bag caught hold of and tore off the end folds of the wrapper so as to make an opening through which the tobacco could be poured. The moment these folds of the paper wrapper were torn away the tobacco was exposed to the air (which easily passed through the meshes of the fabric of which the bag is made) and rapidly dried and deteriorated in quality.

The object of my invention is to avoid opening the end folds of the wrapper within which the tobacco is inclosed, and to pour out the tobacco through a transverse slit, which, (when the mouth of the bag is opened) is made by pulling a tearing cord; said slit being opened by simply squeezing together the sides of the end of the package, and closed by pulling the looped cords of the mouth of the bag in opposite directions. This I accomplish in the manner hereinafter fully described, and as particularly set forth in the claims.

In the drawings: Figure 1 is a perspective view of my improved package showing the mouth of the bag open. Fig. 2 is an end view of said package with the mouth of the

bag open and with the tearing cord and the folded end edges of the paper wrapper intact. Fig. 3 is a similar view of the same after the tearing cord has been pulled out and a slit torn in the crease of one of the folds of the paper wrapper. Fig. 4 is a vertical section of a fragment of said package showing the crease of the fold thereof after tearing. Fig. 5 is a vertical section of the same taken on dotted line 5—5; Fig. 3, and showing the crease before tearing. Fig. 6 is a perspective view of said package with the bag open and the package compressed by hand to pour the tobacco out. Fig. 7 is an end view of the package with the edges of the mouth of the bag of the package drawn tightly together to close the same.

The package shown in the drawings comprises an inner wrapper A which consists of a rectangular sheet of comparatively stiff paraffin paper in which the tobacco is wrapped in the same manner as a grocer wraps a package of sugar or flour or other commodity by bringing the longitudinal edges together and by tucking the portion of the ends extending from the top of the package down over the commodity so as to make an end *a* for closing the same, then tucking the portion of the ends extending from the sides of the wrapper toward each other over said end *a* and forming angular folds *b*, *b*, that reinforce and lap against and assist in holding said end *a* closed, and then folding up the portion of the ends extending from the bottom of the wrapper to form flaps *B* that lap over the angular folds and portion of end *a* left uncovered between said folds *b*, *b*. This is such a common form of package in universal use that no attempt has been made to illustrate it, and the side and end edges are usually held together by tying a cord around the package both longitudinally and transversely. The package to which my improvements are applied dispenses with the usual tying cord, however, and retain the ends of the wrapper in their folded closed relation simply by countersinking the ends of the wrapper so as to leave a marginal bead C at each end. This wrapper is inclosed in a close fitting bag D of cloth or other suitable material the end edges *d* of the mouth of which are cased or hemmed, and two looped cords or draw-strings *e*, *e*, are threaded through the casing in such manner that one end portion of one of said loops extends out of the casing to one side of the mouth of the

bag and one end portion of the other loop extends out of the casing at the other side of said mouth. By pulling said "draw-strings" in opposite directions away from each other the mouth of the bag can be made to pucker and close tightly over the adjacent end of the wrapper, or by inserting the finger in said mouth it can be stretched and opened.

10 The foregoing description relates to a package of tobacco now extensively advertised and in general use, and my improvement comprises simple means for enabling the end of the wrapper to be opened to pour out the fine-cut tobacco without necessitating the tearing off of the flap B, the folds b, b, and more or less of the end a and so as to leave said parts in their relative positions so that when the "draw-strings" are 15 pulled and the mouth of the bag is closed the ends of the parcel inclosed by the wrapper will effectually close the same and shut out the air and keep the tobacco fresh and moist and preserve its aroma and spicy 20 taste. In order to accomplish this I thread a cord E through the bead at the root of flap B from a point near one side of the end of the parcel to the other and extend the ends of said cord E out through minute 25 openings and tie them together. When it is desired to open the package the mouth of the bag is opened and cord E grasped and pulled hard enough to tear open the outer fold of the bead at the root of the flap to 30 form a mouth G and then the adjacent end of the parcel is squeezed between the thumb and fingers, as shown in Fig. 6 of the drawings. This causes the mouth G to open and then as much of the tobacco as desired can 35 be poured out. When the squeezing pressure on the end of the parcel is released, the mouth G will close and the lips, formed by tearing the bead, will come together, if the material of the wrapper is stiff enough. 40

45 If said mouth should remain partially open after pouring out the desired quantity of tobacco, it can be effectually closed by simply pulling the draw-strings and closing the mouth of the bag D tightly.

50 What I claim as new is:

1. A package of the kind specified com-

prising an inner paper wrapper, a bag inclosing the same, and a draw-string for closing the mouth of said bag, and a cord threaded through the edge at one of the 55 sides of said wrapper adjacent to the mouth of the bag.

2. A package of the kind specified comprising an inner paper wrapper, the end edges of which are folded so as to leave an 60 outer flap, a bag inclosing the same, a draw-string for closing the mouth of said bag, and a cord threaded through the edge of said wrapper at the base of said flap from side to side of the wrapper, as and for the 65 purpose set forth.

3. A package of the kind specified comprising an inner paper wrapper the end edges of which are folded to form the ends of the parcel and so as to leave an outer 70 flap, and then said parcel ends countersunk to form marginal beads, a bag inclosing said wrapper, a draw-string for closing the mouth of said bag, and a cord threaded through the bead at the base of said flap 75 and adapted when pulled to make a mouth out through which the contents of the parcel could be poured, substantially as set forth.

4. A package of the kind specified comprising an inner paper wrapper the ends of which are folded to form the ends of a suitable parcel and so as to leave an outer flap and then said ends countersunk to provide marginal beads, a cloth bag inclosing 85 said wrapper the edges of the mouth of which are cased, looped strings threaded through said cased edge that constitute draw-strings for closing said mouth, and a cord threaded through the bead at the base 90 of the flap the ends of which extend out of the bead and are tied together outside said wrapper, which cord is adapted when pulled out to form a mouth which will open when the adjacent end of the parcel is 95 squeezed transversely and will close when the mouth of the bag is drawn closed.

In witness whereof I have hereunto set my hand this 6th day of December, 1915.

WILLIAM L. FROSS.

Witness:

FLORENCE MITCHELL.
